UNITED STATES PATENT OFFICE.

EDWARD MARTIN MONAGHAN AND RICHARD RIGBY, OF LIVERPOOL, ENGLAND, AS
SIGNORS TO THE BRITISH REINFORCED CONCRETE ENGINEERING COMPANY LIMITED, OF MANCHESTER, ENGLAND.

TOOL OR APPARATUS FOR BENDING METAL FABRIC.

Application filed June 6, 1922. Serial No. 566,259.

To all whom it may concern:

Be it known that we, EDWARD MARTIN MONAGHAN, of the city of Liverpool, in the county of Lancaster, a subject of the King of Great Britain and Ireland, and RICHARD RIGBY, of the city of Liverpool, in the county of Lancaster, England, a subject of the King of Great Britain and Ireland, have jointly invented an Improved Tool or Apparatus for Bending Metal Fabric, for which we have made application for patent in Great Britain and Ireland, No. 15,662, dated June 7th, 1921, of which the following is a specification.

This invention relates to the bending of metal fabric and particularly such as is used in building construction in the reinforcement of concrete and the invention will be described in detail in this particular application of it.

In reinforced concrete work and principally where slabs or floor portions extending between and over beams are to be reinforced, the fabric customarily employed is made up of parallel longitudinal wires spaced regularly apart (and some 25 to 30 in number) and united by regularly spaced transverse wires welded thereto. The desired disposition of this fabric in the finished slab is such that over the beams it is near the top of the slab and between the beams it is near the bottom of the slab and this involves a regular cranking or bending of the fabric which as far as we are aware has hitherto proved impracticable or has involved slow and unreliable operative procedure.

It is an important feature of the invention to overcome this difficulty and the invention provides for obtaining the desired result with certainty with extraordinary celerity and by means of so simple a character and robust a form as to satisfy the peculiar requirements of building operations.

One feature of the invention is a metal fabric bending apparatus comprising means (e. g. hooks passed between the strands) to enter into engagement on a line transverse to the strands, with a plurality of strands of the fabric by movement (between said means and the fabric) having a component transverse to the general plane of the fabric, means (e. g. the edge of a plate) to engage the fabric at the same part of its width

on a line substantially parallel to aforesaid line and from the same face of the fabric as that from which the first mentioned means entered into engagement with the said strands, and means (e. g. a long handle) for causing the two aforesaid means respectively to exert oppositely directed pressures on the fabric to bend the portions of said strands between the lines aforesaid relatively to portions of the strands beyond the same.

Another feature of the invention is in the production of reinforced concrete the employment of an apparatus which at one application of the apparatus to reinforcing fabric comprising parallel strands of wire bends a plurality of the strands by applying to each strand, simultaneously at points spaced apart along it, oppositely directed forces transverse to the general plane of the fabric.

The above and other object and features of the invention will become fully evident to those skilled in the arts in question from a consideration of the following description with reference to the accompanying drawings of two forms of hand tool according to the invention.

In the accompanying drawings:—

Figure 1. is a diagram indicating generally the problem presented in the case of 85 that application of the invention which is particularly under consideration.

Fig. 2. is a side, part sectional, elevation of a hand tool according to the invention for bending the fabric in the manner required 90 for reinforced work as indicated in Fig. 1.

Fig. 3. is a front elevation of the tool shown in Fig. 2.

Fig. 4. is an inverted plan view of the tool, and

Fig. 5. is a diagram illustrating the mode of operation of the tool.

Fig. 6 shows diagrammatically a modified form or tool according to the invention.

The tools shown are intended to bend at 100 a single operation seven of the strands of the reinforcing fabric although the same may be designed, as will be evident, to bend simultaneously any larger or smaller number of the wires. They are intended to bend the wires more or less as indicated in Fig. 1 so that a gentle slope of say 30° or thereabouts connects the portion 3 of the wire

which is to be (between the beams 5, 5) near the bottom of the slab 7, with the portion 9 which is to lie over the beams, near the upper surface of the slab.

5 Referring now to Figs. 2, 3 and 4, the tool has a bed plate 11 from the front edge of which depends a number of hook members 13 with bevelled portions 13^x. These may be formed by cutting out portions of 10 the plate 11, made in such a case of angle iron, or may be secured to or in the plate 11. There is an eighth member or guide 15 which is not hooked. The seven openings 16 between the hooks and between the guide 15 and adjacent hook are spaced apart at a spacing corresponding to that of the wires of the fabric but the openings are substantially wider than the thickness of the wires so as to facilitate the entry therein of the 20 fabric even when, as commonly occurs, wires of the fabric are somewhat distorted laterally.

An extension plate 18 is secured underneath the bed plate by bolts 20 secured to 25 it (the plate 18) and clamping nuts 22 threaded on to the bolts, the latter passing through slots 24 in the bed plate so that the extension plate may be clamped in different 30 positions to the bed plate. A long handle 26 is suitably secured rigidly to the bed plate and has pivoted thereto at 28 a leg 30 which straddles an arcuate member 32 provided 35 with a series of holes 34 with any of which a thumb screw 36, passing through appropriate holes in the leg, may co-operate to lock the leg in definite angular relationship to the handle.

The fabric having been spread out upon 40 the bottom of the mould or form of temporary floor the workman lowers the tool upright upon the section to be bent and with the guide 15, which is longer (say by some three-eighths of an inch) than the hooked members, between the last of the group of 45 wires to be bent and the next adjacent wire which is not then to be bent or has already been bent. He then slides the tool laterally over the surface of the fabric so as to move the guide towards said last wire of 50 the group, and in this way the tool is, without special attention on his part, brought to a position in which the group of wires will be opposite the openings 16 and the tool then drops home on to the fabric with the 55 respective wires between the hooked members. The extra length of the guide prevents excessive movement of the tool in the direction referred to. The tool is now moved back in the opposite direction to bring 60 the wires behind the horizontal portions of the hook members 13 and the operation of engaging the tool with the group of wires is complete. It will be evident that by reason of the provision of the guide 15 this 65 operation can be easily and quickly per-

formed. The actual bending is then a mere matter of tipping the tool, with the edge of the extension plate pressed down upon the fabric, until the free end of the leg 30 meets the bottom of the mould (see Fig. 5) 70 the weight of the fabric beyond the hooks, or, it may be, pressure applied (as indicated in Fig. 5 by the arrow), by the workman on the fabric just past the hooks completing the double bending. 75

This supplementary duty disappears if, as may be done when desired, two workmen each use a tool at the same time to form the opposite bends in the fabric at each side of a beam location in the mould. 80

It will be evident from a consideration of Fig. 5 that the adjustment of the extension plate 18 relatively to the bed plate 11, which the slots 24 allow of, determines the length of the inclined portion of the wire, i. e. the 85 length AB, while the inclination at which the leg 30 is set relatively to the handle 26 determines the inclination of the bend, i. e. the angle at D.

When the bending of one section is complete the fabric is released by tipping the tool back a little and performing the opposite movements to those by which the tool was threaded upon the fabric, the bevelled 90 portions 13^x of the hooks facilitating the unthreading. The tool may then be moved laterally to the next section of the fabric and the whole width of it bent step by step in this way. 95

In Fig. 6 is indicated an addition to 100 such a tool as has been described, which addition positively secures that both bends which go to give the wire its cranked form shall be made by the tool and at the single 105 operation. The handle 26^x which is conveniently cranked as indicated is not rigidly secured to the plate 11 but is pivoted thereto as at 40. Projecting from it is a cam piece 42 acting upon one arm 44 of a lever pivoted at 46 to the plate 11 and the other 110 arm of which at its end has a cross bar 48 rigidly secured to or in one therewith and extending along the row of hooks from end to end and parallel thereto. A spring 50 secured to the handle 26^x and bearing on the arm 44 normally holds the cam 42 down on the plate 11, so as to bring the handle upright in relation to the plate, and holds the cross bar 48 elevated so as not to impede threading of the tool on to the wires. 115 To the back of the handle is secured a spur piece 52 adapted to limit the relative movement of the handle and plate 11 about the pivot 40. This piece 52 is adjustable heightwise of the handle, being slotted for the passage of clamping bolts 54 and having teeth of say one eighth of an inch pitch to engage similar teeth on the handle which resist movement of the spur piece heightwise of the handle and so assist the clamping 120 125 130

bolts. The device having been threaded upon the wires in the manner already described pressure upon the tool handle, forcing the leg 30 down on the bottom of the mould 5 and the free edge of the plate down on the fabric resting on the bottom of the mould, causes relative movement of the plate 11 and handle 26* (until the spur piece bears upon the plate 11) which moves the cam piece 42 along the rear surface of the lever arm 44 thus camming the lever about its pivot, against the action of the spring 50, and lowering the cross bar 48 forcibly upon the fabric to bend it beyond the hooks as indicated. The adjustment of the spur piece on the handle determines the angle of the bend thus formed beyond the hooks, which for any given setting of this spur piece the adjustment of the leg 30 relatively to the handle determines, as already described, the 20 angle of the other bend.

What we claim is:—

1. Apparatus for bending metal fabric comprising a handle an adjustable plate on 25 said handle, the rear edge of which is adapted to engage and bend a plurality of strands of the fabric and means on said handle forward of the said adjustable plate, to engage the opposite side of the fabric, 30 as set forth.

2. Apparatus for bending metal fabric comprising a handle, a bed plate on said handle, an adjustable extension plate on the bed plate, means on said bed plate to pass

through and engage the opposite sides of a 35 plurality of strands of the fabric along a line parallel to the rear edge of the adjustable plate, substantially as described.

3. Apparatus for bending metal fabric comprising a handle, a bed plate on said 40 handle, means on said bed plate to engage a plurality of strands of the fabric along a line parallel to the rear edge of the plate, an adjustable extension plate on the bed plate, and an adjustable leg to limit the 45 inclination of the bed plate, substantially as described.

4. Apparatus for bending metal fabric comprising a manipulating handle, a bed plate on said handle, a plurality of hooks 50 along one edge of the bed plate with the open ends towards one end, an adjustable extension plate at the other edge of the bed plate and an adjustable stop to limit the turning movement of the bed plate, sub- 55 stantially as described.

5. Apparatus for bending metal fabric comprising a handle on said bed plate, a plurality of hooks along one edge of the 60 bed plate, an adjustable extension plate at the other edge of the bed plate, a handle and means to limit the turning movement of the handle about the extension plate, substantially as described.

In testimony whereof they have signed 65 their names to this specification.

EDWARD MARTIN MONAGHAN.
RICHARD RIGBY.
